UNITED STATES PATENT OFFICE.

GIUSEPPE DALLA BONA, OF COMO, ITALY.

AUTOMATIC APPARATUS FOR SIGNALING RAILROAD TRAINS IN MOTION.

Application filed August 11, 1921. Serial No. 491,503.

To all whom it may concern:

Be it known that I, GIUSEPPE DALLA BONA, subject of the King of Italy, residing at 9 Via Indipendenza, Como, Italy, have invented certain new and useful Improvements in Automatic Apparatus for Signaling Railroad Trains in Motion, of which the following is a specification.

As is well known, a magnetic mass which 10 has its main axis set vertically becomes magnetized by effect of the magnetism of the earth and this magnetism increases, causing the mass to vibrate: to this principle are subjected the wheels of railroad cars, which may 15 therefore be considered, each one of them, as a magnet having its north pole below and its south pole on top.

The object of the present invention is a 20 special automatic apparatus which receives the excitation transmitted by the magnets represented by the wheels of the railroad cars and which has its north polarity below and its south polarity on top, and contemplated to be placed either laterally, at some 25 metres of distance from the railroad track, or between the two rails of the track, without having any communication with the train in motion and with the rails themselves.

30 The present invention relates further to a receiving apparatus, contemplated to be substituted for the automatic apparatus when the latter cannot be placed between the two rails of the track.

35 The invention also relates to a special device which generates an electric current for feeding the said receiving apparatus without necessitating the installation of batteries of cells or of accumulators which require 40 special maintenance.

Finally, the invention comprises a special modified relay, to be applied to the system, as will be explained hereafter.

The invention is illustrated in one of its 45 forms of execution in the annexed drawings, in which:

Fig. 1 is a diagrammatic view in perspective of the automatic receiver of the flux.

Fig. 2 shows the oscillating magnet forming part of such automatic apparatus.

Figs. 3, 3^a, 3^b show, in three different positions, the contact pawl.

Fig. 4 is a plan view of the interior of the receiving apparatus.

Figs. 4^a and 4^b show, in elevation respectively the pawl which closes the contacts and the regulating device.

Fig. 5 shows the electrode cell buried in the ground, used for actuating the circuits.

Fig. 6 shows a box for containing the 60 automatic apparatus.

Fig. 7 shows the box placed between the rails of a railroad track.

Fig. 8 shows the general diagram of the 65 circuits.

The automatic apparatus (Fig. 1) consists of a circular or polygonal base 1, of non magnetic material, carried on three screw legs 2 and which carries in its centre a hardened steel pivot 3 on which rests, in 70 perfect static equilibrium, the magnet 4 by means of the pointed screw 5. This magnet (Fig. 2) consists of a bar of hardened steel, magnetized to saturation, which carries at each end the projections of soft iron 6, 7 and the platinum wire contacts 8 and 9. In front of the said projections are arranged, 75 fixed to the base 1 by means of the respective brass brackets 10, the two coils 11, 12, each having a resistance of 400 ohms, having in 80 the centre an axial hole into which can freely enter, and issue therefrom, the projections 6, 7, and, in correspondence with the contacts 8, 9, there are also fixed to the base, by means of brass brackets, the two pawls 13, 85 14 of hardened aluminum, provided with platinum wire, (not shown) adapted to slide on the contacts of the magnet. Below each pawl, and fixed by means of a screw to the respective bracket, is a support 15 made in 90 the form of an S, which serves to sustain the short arm of the pawl, causing it to be held at the desired inclination towards the magnet. Each pawl must freely rotate, 95 vertically, on its screw pivot.

Mounted on the base 1 is a bracket 16 having a vertical slot 18 in which is adjustably mounted a screw button which serves to adjustably secure a small brass spindle 17 in the path of movement of the magnet 4. By 100 adjusting the spindle to right or left in the body of the screw button, the end of the spindle can be made to approach, or to recede from, the magnet. This spindle has the object of arresting or reducing the oscillations of the magnet as soon as the electric circuit to be described later is interrupted.

The apparatus described should be placed

exactly horizontal and at a distance of not more than 4 metres from a railway track and between the two rails, in a special recess, 19, having a cover 20 (Fig. 6) of reinforced concrete, excavated between two consecutive sleepers. In both of the positions described, the apparatus should rest on a solid mortar foundation so as to render it as little as possible responsive to the ground shocks caused by the passing of the train.

10 The magnet should besides be placed according to the meridian of the site, with the contacts 8, 9 at a certain distance from the pawls 13, 14. The apparatus is introduced, 15 by means of the cable 24, into the electric circuit of a station cell 21 with the switch 22 and bell 23, and it will then be ready for working (Fig. 1).

When the apparatus is to work by direct 20 action, that is to say, when a single vehicle or a train passes before or over it, the magnetic attraction due to the wheels will cause the magnet 4 to deviate towards the pawls and contact with the latter having been obtained, 25 the current will flow through the pivot 3 of the magnet, through the pawl 13 to the coil 11 and partly through the pawl 14 to the bell 23 and finally reenter the cell. The coil 11 (energized by the said current) will attract 30 the magnet and draw the projection 6 into its axial hole and thus transform itself into an electromagnet with a metal core. And as the pawl 13 will continue to rest on the contact 8 of the magnet, the current will continue to flow, the circuit remaining thus 35 closed until the switch 22 is operated. As soon as the circuit is interrupted, the action of the coil 11 will cease and there now being nothing to retain the magnet against the 40 said coil, the magnet, moved by its magnetic bias and also by the thrust, in the same direction, of the pawls, will deviate with a certain rapidly towards the part opposed to the coil, its other end striking against the spindle 17, which arrests it.

If it is not convenient, for various reasons, 45 to place the apparatus between the two rails of a track, the same object is obtained by substituting the magnetic receiver (Fig. 4) 50 which acts as an auxiliary to the automatic apparatus. This receiver consists of a wooden box 25, containing a magnet 26, identical with the one already described but without the projections 6, 7 and suspended in 55 perfect static equilibrium on a pivot 3, similarly to the one already described, fixed centrally to the bottom of the box. In correspondence with the two ends of the magnet are also fixed to the bottom of the box, 60 the pawl 27 and the regulating organ 17 with its small spindle, except that this organ, in this case, will have attached to its extremity nearer the magnet a small piece of soft iron 28.

65 The contrivance as described should be

placed in an exact horizontal position on the bottom of the recess 19 and is fed by a specially constructed cell with its electrodes buried in the ground.

This disposition is obtained in the following manner:

After having excavated a hole (Fig. 5) in the ground adjacent to the track, the said hole is filled with good vegetable earth, homogeneous, free from stones and small pebbles, and with which has been previously mixed 2 kilos of a good chemical fertilizer (ammonium sulphate or sodium nitrate or natron chloride) to render it rich and fertile. In the said earth, which should be fairly well compressed, is sunk, in the central portion, a zinc plate 29 and a charcoal plate 30. To each plate is soldered a robust lead wire or electric cable which traverses, perfectly insulated, the mass of earth above. The bottom of the said hole is constituted by a layer of fine mortar so as to maintain in the mass of earth above a sufficient and constant grade of humidity.

This cell has the property of furnishing for an indefinite period a constant and uniform current from 8 to 15 milliamperes without ever requiring maintenance. Such current is contemplated, by means of the receiver already mentioned, to energize the coil 12 of the automatic apparatus for obtaining the indirect function hereinafter described.

The automatic apparatus is placed also at a considerable distance and height from the track, exactly horizontal, and in such position that the magnet, instead of being free in its natural disposition according to the local meridian, exerts a slight pressure with its contacts against the respective pawls 27: 105 it is introduced into the circuit of the local cell 21 with the switch 22 and the bell 23.

The magnetic receiver, placed, as previously explained, on the bottom of the hole between the two rails (Figs. 1, 4 and 5 and dotted lines of connection and diagram in Fig. 8, in which A is the main magnetic apparatus shown in Fig. 1, B, B' the track, P the receiver shown in Figs. 4, 4^a and 4^b, p a local cell, q the cell shown in Fig. 5, I the switch and S the bell) will have its magnet, in its natural position, in slight contact with its pawl 27. By means, then, of the regulator 17, by which it is possible to regulate the distance of the magnetic end 28 from the magnet, means will be afforded for adjusting the pressure of the magnet itself against the pawl and hence its sensitiveness to the external magnetic attraction of the wheel of a car passing over the track with which it is associated in such a manner that whilst it is actuated by a single railroad vehicle which passes over the track with which it is associated, it will not be at all affected by the vibration caused

by rather heavy or rapid trains passing over the adjacent tracks (minimum distance 2 metres).

The receiver is thus introduced into the circuit of the cell *q* shown in Fig. 8 and of the automatic apparatus, being connected to the coil 12 of the latter. All the foregoing being arranged in accordance with the system, the current of the cell *q*, by means of 10 the receiver, will pass to the coil 12 of the automatic apparatus and energizing it in the sense of repulsing the magnet to a certain distance (adjustable) from the pawls, the magnet will remain fixed in that position 15 ready to function due to the constancy of the current.

When a railroad car passes over the receiver, the magnetic flux of its wheels causes the magnet to deviate, detaching it from the pawl, whereby the current of the cell *q* is 20 cut out and, consequently, the repulsive action of the coil 12 of the automatic apparatus ceasing, its magnet 4, will return to its normal position, pressing with a certain 25 force against the fixed pawls, the local cell will at once enter into action with the known effects, thus obtaining the signal or service desired. After the car has passed, the magnet of the receiver will return immediately 30 to its former position, ready for working, again closing the circuit of the cell *q*.

When, finally, the station cell circuit is 35 cut out by means of the switch I, the magnet of the automatic apparatus being no

longer retained by the coil 11 and repulsed instead by the coil 12 and under the thrust of the pawls, will return to its position of readiness.

Having now particular described and ascertained the nature of my said invention and in what manner the same is to be performed, I declare that what I claim is:—

1. Automatic apparatus for signaling running railroad trains consisting of a 45 metal bar rotatably mounted on a pivot and placed in such proximity of the rails as to be subjected to the magnetic attraction from the wheels of the cars, said bar being provided with two contacts and two projections, pawls connected to a local circuit comprising a battery and a bell, said pawls being so placed as to be engaged by the bar when same oscillates due to the passage of a train, a coil in the electric circuit, said coil having an axial recess into which is drawn one of the projections on the bar as soon as the local circuit is closed by the pawls, and a horizontal spindle to damp the oscillations of the bar as soon as the 50 circuit is interrupted.

2. Automatic apparatus for signaling running railroad trains, as claimed in claim 1 in combination with a receiver of substantially the same construction as the main apparatus, the contacts of which are in series with the cell and with one electromagnet of the automatic apparatus.

GIUSEPPE DALLA BONA.
